THOMAS J. MULLEN AND WILLARD C. POWELL, OF DAYTON, OHIO, ASSIGNEES TO OSCAR M. POOCK, DOING BUSINESS AS THE CITY MACHINE & TOOL WORKS, OF DAYTON, OHIO

GEAR POLISHING MACHINE

Application filed April 28, 1930. Serial No. 443,077.

This invention relates to a machine for polishing gears or for like purposes and one object of the invention is to provide such a machine which will quickly and efficiently 5 polish a gear and which will act upon a large number of gears in rapid succession.

A further object of the invention is to provide a gear polishing machine having means for automatically reversing the direction of 10 rotation of the polishing members and for subsequently automatically interrupting the rotation of the polishing members.

A further object of the invention is to provide means for automatically feeding a 15 succession of gears into position to be acted upon by polishing members.

A further object of the invention is to provide improved means for moving one of the polishing members toward and from 20 another polishing member and for advancing the gears which are to be polished in timed relation to the movement of the movable polishing member.

A further object of the invention is to 25 provide such a machine which will be simple in its operation, easily controlled and which will be of a strong durable character.

Other objects of the invention will appear 30 as the mechanism is described in detail.

In the accompanying drawings Fig. 1 is a front elevation of a machine embodying our invention; Fig. 2 is a side elevation of the same; Fig. 3 is a top plan view of such a machine; Fig. 4 is a transverse sectional view taken on the line 4-4 of Fig. 1; Fig. 5 is a vertical sectional view taken on the line 5-5 of Fig. 4; Fig. 6 is a sectional detail view taken on the line 6-6 of Fig. 4; Fig. 7 is a sectional detail view taken on the line 7-7 35 of Fig. 5; Fig. 8 is a front elevation of the controlling mechanism for reversing the direction of rotation of the polishing members; Fig. 9 is a sectional detail view of the reversing mechanism; Fig. 10 is a plan view of the 40 polishing members showing a gear in position to be polished; and Fig. 11 is a detail view of the conveyor actuating device.

In these drawings we have illustrated one embodiment of our invention and have shown 45 the same as applied to a gear polishing ma-

chine but it will be understood that this embodiment has been chosen for the purposes of illustration only and that the mechanism may take various forms and may be used for various purposes without departing from the spirit of the invention.

As here illustrated the machine comprises a base or pedestal 10 on which the various parts of the operating mechanism are supported. In this machine we utilize a plurality of operating members, preferably 50 three, which are so arranged that when in their operative positions all of them will engage and act upon a single article. As here shown, the operating members are in the form of toothed polishing members adapted 55 to engage and to intermesh with the teeth of a gear which is to be polished. One of the polishing members, 11, is mounted for rotation about a normally fixed axis and the other 60 two polishing members, 12, are mounted for bodily movement toward and from the polishing member 11. While the polishing members 12 are in their retracted positions a gear 65 is placed in such relation to the polishing member 11 that when the polishing members 12 are moved toward the polishing member 11 all three polishing members will be caused 70 to engage the gear which is to be polished. The polishing members are rotated first in one direction and then in the other direction 75 to polish both sides of the teeth of the gear. In the position of the parts shown in Figs. 4 and 5 the polishing members 12 are in an inner position close to the polishing member 11, to act on a very small gear, while in Fig. 10 the polishing members 12 are 80 spaced from the polishing member 11 a distance sufficient to receive and act on a larger gear, as shown at 90.

The member 11 is here shown as rigidly secured to the lower end of a vertical shaft 13 which is journaled in an elongated bearing 14 carried by a supplemental frame or housing 15 supported on the main frame or base 10. Preferably the shaft which carries the polishing member 11 is transversely adjustable to accommodate it to gears and polishing members of different diameters. As here shown, the bearing 14 for the shaft 95

100

13 is secured to and, if desired, may be formed integral with, a plate 16 which is slidably mounted at the lower side of the housing 15. The plate 16 has an upwardly extending lug 17 provided with an opening into which is threaded a screw 18 which is rotatably mounted in the end wall of the housing, held against axial movement with relation thereto and provided with a hand wheel 19, whereby the plate and the shaft 13 may be adjusted. A locking screw 20 is threaded into the upper part of the lug 17 and extends upwardly through a slot 21 in the top wall of the housing and through a plate or washer 22 resting upon the top wall of the housing and has mounted thereon, above the plate 22, a nut 23 by means of which it may be rigidly secured in position to hold the plate 16 and bearing 14 against movement. Rotatably mounted in the housing 15 is a driving shaft 24 having driving connection with the shaft 13. As here shown, the shaft 24 is provided with a worm 25 which meshes with a worm wheel 26 on the upper end of the shaft 13. One end of the shaft 24 projects beyond the end of the housing 15 and has mounted thereon a belt pulley 27 to receive a belt 28 by means of which it is connected to the shaft 29 of an electric motor 30.

The motor 30 is of the reversible type and is controlled by a reversing switch, which is not shown but which is enclosed in a casing 31 and comprises in part an actuating member or shaft 32 which projects beyond one side of the casing. By manipulating the actuating member or shaft 32 the switch may be initially closed to cause the motor to rotate in one direction, then shifted to a position which will reverse the flow of current through the motor and cause the latter to rotate in the opposite direction, and may then be moved to a neutral position which will open the circuit and interrupt the operation of the motor. In the present device, the initial operation of the switch actuating member, to place the motor in operation, is effected manually and to this end an operating handle 33 is connected with the actuating shaft 32. The reversing and stopping movements of the switch are imparted thereto automatically and the mechanism is so arranged that the polishing member will be given a predetermined number of rotations in one direction, then reversed and given a predetermined number of rotations in the opposite direction and then stopped. To accomplish this we have provided a controlling mechanism which is driven from the motor. As here shown, a transverse shaft 35 is journaled in the bearing 36 carried by the side wall of the housing 15 and has at its inner end a worm gear 37 meshing with a worm 38 on the driving shaft 24. The shaft 35 projects beyond the side of the housing 15 and

has mounted thereon a controlling member or disk 39 which is so connected with the shaft that it will normally rotate therewith but the connection is preferably a frictional one, as shown, so as to permit the shaft to have movement with relation to the disk, as will be hereinafter explained. Arranged axially of the controlling member 39 and projecting beyond the outer face thereof is a stud 40 which is rotatable with relation both to the shaft and to the controlling member or disk. As here shown, the stud has a part 41 extending into a recess in the end of the shaft and is held against axial movement by contact with a boss 42 in the closure plate 43 for the housing 43 which encloses this part of the mechanism. The shaft 35 has driving connection with the controlling member or disk 39 but this connection is preferably in the nature of a slip connection to permit the shaft to rotate with relation to the disk under conditions which will hereinafter appear. For this purpose the shaft 35 is provided at its end with a disk-like enlargement or plate 144 which is rigidly secured thereto and may, if desired, be formed integral therewith. This plate 144 is connected with the disk by means of a ring or collar 145 having an inwardly extending flange 146 which overlaps the rear face of the plate 144 on the shaft. A ring of fiber or other friction material 147, is interposed between the flange 146 and the plate 144 and a disk of fiber or other friction material 148 is interposed between the disk and the outer face of the plate 144. The collar or ring 145 clamps the friction material firmly in engagement with the plate 144 and preferably the ring is spring pressed so as to exert a constant pressure thereon. As here shown, a series of bolts 149 are mounted in the disk 39 and a ring is slidably mounted on these bolts, springs 150 being interposed between the ring and the heads of the bolts so as to press the ring toward the disk and thus establish a firm frictional connection between the shaft and the disk. Mounted on the stud 40 and extending radially therefrom is an arm 44 which is preferably slidably mounted in a transverse opening in the stud. Pivoted to the outer end of the arm 44 is a link 45 the other end of which is rigidly secured to the switch actuating shaft 32. The controlling member or disk 39 is provided with suitable parts arranged to engage the opposite sides of the arm 44 and actuate the same, these parts being preferably adjustable with relation to the disk to properly time the operation of the arm. As here shown, these parts are in the form of studs 46 and 47 adjustably mounted in an annular groove 48 in the face of the disk.

When the actuating handle 33 is operated to close the circuit and place the motor in operation the link 45 will move the arm 44

to the full line position shown in Fig. 8, the arm 44 sliding in the stud 40 to compensate for the longitudinal movement due to the different centers about which the link and the 5 arm move. As the motor rotates to drive the polishing member in one direction it also drives the disk 39 in a corresponding direction but the ratio of the gearing is such that the disk will rotate at a relatively slow speed. 10 The movements of the polishing member and of the disk are so timed that when the polishing member has made the desired number of rotations the stud 46 on the disk 39 will engage the arm 44 and move the same to the 15 dotted line position shown at 44a in Fig. 8 and this movement of the arm will cause the link 45 to actuate the reversing switch to reverse the flow of current through the motor and thus cause the motor shaft to rotate in 20 the opposite direction which, of course, causes the polishing member and the disk 49 to rotate in reverse directions. When the polishing member has made the desired number of rotations in a reverse direction the stud 25 47 on the disk 39 will engage the arm 44 and move the same to the position shown in dotted lines at 44b in Fig. 8 and this movement of the arm will cause the link 45 to turn the switch actuating shaft 32 to its neutral position, thus interrupting the operation of the 30 motor and of the parts connected therewith. Due to its momentum the motor will have a certain amount of movement after the switch has been moved to its open position but the 35 frictional connection between the shaft 35 and the disk 39 will permit of this further operation of the motor without affecting the positions of the several parts of the controlling device. The switch may take various 40 forms and may be provided with any suitable means, such as a cam, for so controlling the switch shaft 32 that the switch may be moved from starting position to reversing position, it being carried across the neutral 45 position by momentum, and then moved from reversing position to neutral position and stopped in neutral position, the slip connection permitting the continued movement of the motor by momentum. Pressure applied to 50 the handle 33 will force the switch out of its neutral position to the starting position. The two bodily movable polishing members 55 12 are carried by a supporting member 49 which is slidably mounted in suitable guide- ways 50 on the main frame of the structure and are freely rotatable about their individual axes. In the present device, the polishing members 12 are not provided with driving mechanism but are rotated by the gear which 60 is being polished and which is rotated by the positively driven polishing member 11. In order to accommodate the polishing members 12 to gears of different diameters these polishing members are carried by blocks 51 65 slidably mounted on the supporting member 49 and provided with means, such as screws 52, for rigidly securing the same in adjusted positions. Preferably the forward edges of the supporting member converge inwardly. Any suitable means may be provided for imparting movement to the supporting member to move the polishing members 12 toward and from the polishing member 11. Preferably fluid operated mechanism is utilized for this purpose, and the fluid operated mechanism here shown is of a well known type and comprises an air cylinder 53 having therein the usual piston, not shown, with which is connected a piston rod 54 which is operatively connected with the slidable supporting member 49. In the present arrangement the piston rod or plunger extends beneath the supporting member and is provided with collars or stops 55 spaced one from the other. A stud 56 mounted on a fixed part 70 of the apparatus extends downwardly through an opening 57 in the supporting member or plate 49 and pivotally supports an arm 58 which extends across the piston rod and is provided with an enlarged portion 75 59 arranged between the stops 55 and having rounded edges to engage those stops. The free end of this arm is connected by a link 60 with a supporting member 49. In the present instance, the arm 58 is arranged below 80 the piston rod and a second short arm 61 is rigidly connected with the arm 58 and is provided with an enlarged end arranged between the stops 55 on the upper side of the piston rod. The admission of air under pressure 85 to the cylinder 53 is controlled by a suitable device arranged adjacent to the operator's station and this device preferably comprises a foot operated valve. As here shown, an air pipe 62 leads from a suitable source of supply for air under pressure, not shown, to a valve 63 which is arranged in the lower part of the base or pedestal 10 and provided with a foot lever 64 by means of which it may be operated. A conduit 65 leads from the valve 100 to the cylinder 53 and communicates therewith on the inner side of the piston so that when the valve is operated to connect the conduits 62 and 65 the piston and the supporting member 49 will be moved outwardly. 105 When the pedal is released and the valve returns to its normal position the cylinder is connected with an exhaust pipe 66. A conduit 67 leads to the cylinder 53 on the outer side of the piston and serves to admit air 110 thereto for the purpose of moving the piston and the supporting member 49 inwardly. In the present arrangement, the conduits 62 and 67 are in constant communication with the outer end of the cylinder but the air is delivered to the cylinder under a pressure substantially less than the pressure of the air delivered on the inner side of the piston by the conduit 65 so that when the valve 63 is 115 opened the high pressure air will force the 120 piston and the supporting member 49 inwardly. 125 When the valve 63 is closed the air will be admitted to the cylinder 53 through the conduit 67 and the piston will be moved outwardly. 130

piston outwardly against the lower pressure in the outer end of the cylinder, and when the valve 63 is closed and the conduit 65 connected with the exhaust the low pressure air 5 will actuate the piston and impart inward or operative movement to the supporting member. As here shown, the conduit 67 is connected with the supply pipe 62 but has interposed therein a pressure regulator 68 10 by means of which the air pressure may be reduced to the desired extent.

While the supporting member 49 is in its retracted position and the polishing members 12 are spaced from the polishing member 11, 15 the gear to be polished is placed in position to be engaged by the three polishing members. The gear may be placed in this position in any suitable manner but we prefer to provide mechanical means for feeding the 20 gears to polishing position so that the device will act on a large number of gears in rapid succession. For this purpose we have employed a conveyor for supporting the gears and moving the same into operative relation 25 to the polishing members. This conveyor may take various forms but is here shown as an endless belt 69 supported by pulleys 70 and having a series of studs 72 mounted thereon and spaced apart lengthwise thereof. 30 In the present arrangement these studs extend through the endless belt and project for some distance beyond both surfaces thereof. The outer ends of the studs are provided with reduced portions or pintles 73 to 35 enter the central openings in the gears and rotatably support the latter. The upper stretch of the conveyor belt extends just below the several polishing members and the studs 72 are of such height that a gear mounted on one of these studs will be supported in proper operative relation to the polishing members. The conveyor may be advanced in any suitable manner but it is preferably advanced step by step in timed relation to 40 the movements of the supporting member 49 which carries the polishing members 12, the movements being so timed that one of the studs 72 with its supported gear will be moved into operative relation to the polishing members each time the supporting member 49 is retracted, so that when the supporting member and polishing members are again moved to their forward positions there will be a gear in position to be engaged 45 thereby. The actuating mechanism here shown comprises an arm 74 pivotally mounted on a vertical axis beneath the supporting member 49 and having at its free end a pawl or dog 75 which is provided with a nose 75a 50 to engage the studs on the inner side of the belt and advance the belt when movement is imparted to the arm 74. A spring 76 acts on the dog to move the same into engagement with the studs and the outer side of the nose 75a is beveled so that when the arm 74

is moved to its initial position the nose of the pawl will ride over the stud and will then be moved into operative engagement therewith. The actuating arm 74 has an elongated hub 77 which is mounted on a vertical shaft 78 and this hub is provided with a circumferential recess arranged to provide a shoulder 79, which shoulder is intersected by a slot 80 in the hub. The hub is arranged in line with the piston rod 54 and this rod 75 extends through the slot 80 in the hub and has on its inner end a head 81 arranged to engage the shoulder 79 and rotate the hub whenever the piston rod is moved in an outward direction, to retract the supporting member 49. This movement of the head 81 imparts operative movement to the operating arm 74 and causes the conveyor to be advanced one step. Any suitable means may be provided for restoring the actuating arm 85 to its initial position where it will engage the next succeeding stud on the conveyor but we have provided fluid operated means for this purpose. The hub 77 has a second circumferential recess arranged to provide a shoulder 82 which is engaged by the end of a plunger 83 mounted in an air cylinder 84 adapted to be connected with a suitable source of supply for air under pressure, not here shown, so that when the next forward 90 movement of the piston rod moves the head 81 out of engagement with the shoulder 79 the pressure on the plunger 83 will rotate the hub to restore the actuating arm to its initial position. Preferably the cylinder 84 is in constant connection with its source of air supply and contains air under pressure at all times but the pressure is sufficiently low to permit the rotation of the hub and of the actuating arm by the piston rod 54 when the latter is retracted. A stop 85 is arranged in the path of the actuating arm 74 to limit its movement by the plunger 83 and, in the present instance, the arm has mounted therein a screw 86 to engage the stop and which 100 may be adjusted to accurately position the dog with relation to the studs on the conveyor.

It will be apparent, therefore, that in the operation of the machine, after a series of 110 gears have been mounted on the conveyor studs, the foot valve 63 is actuated to admit air to the cylinder 84 and thus cause the polishing members 12 to move into their operative positions adjacent to the polishing member 11. The conveyor having been actuated when the supporting member 49 was last retracted there will be a gear in position to be engaged by the several polishing members. The switch actuating shaft is then manipulated to start the motor. After the motor has rotated the polishing members in one direction for a predetermined number of rotations it is automatically reversed and will rotate the polishing members in the opposite 120 direction. The conveyor is then advanced 125 and the supporting member 49 is retracted so that the gear will be engaged by the polishing members 12. The switch actuating shaft is then manipulated to start the motor. After the motor has rotated the polishing members in one direction for a predetermined number of rotations it is automatically reversed and will rotate the polishing members in the opposite 130 direction. The conveyor is then advanced and the supporting member 49 is retracted so that the gear will be engaged by the polishing members 12.

direction for a predetermined number of rotations, after which the motor is stopped. The foot valve is then released to permit the air to be exhausted from the outer end of the cylinder and cause the supporting member and polishing members 12 to be retracted. This operation causes the actuating arm 74 to be moved about its axis and to advance the conveyor a distance sufficient to move the polished gear beyond the polishing members and to move another gear into operative relation to the polishing members, and the cycle of operations above described is then repeated. It will also be apparent that the apparatus may be utilized in part or as a whole for performing work other than the polishing of gears, by merely substituting the operating members for the polishing members and mounting the article on which the work is to be performed on the device which in the present device supports the gear which is to be polished.

While we have shown and described one embodiment of our invention we wish it to be understood that we do not desire to be limited to the details thereof as various modifications may occur to a person skilled in the art.

Having now fully described our invention, what we claim as new and desire to secure by Letters Patent, is:

1. In a machine of the character described, a plurality of rotatable operating members, means to support an article in a position to be operated on by said members, a reversible motor, means driven by said motor to rotate one of said operating members, a shaft driven from said motor, a disk connected with said shaft for rotation therewith, a stud projecting beyond the face of said disk and rotatable with relation thereto, a radial arm slidably mounted on said stud and rotatable therewith, parts carried by said disk to engage the respective sides of said arm and actuate the same, a switch actuating shaft, and a link rigidly secured to said switch actuating shaft and pivotally connected with said arm.

2. In a machine of the character described, an operating member mounted for rotation about a normally fixed axis, means for actuating said operating member, a movable supporting member, a second operating member rotatably mounted on said supporting member and movable therewith toward and from the first mentioned operating member, a conveyor having means for supporting a plurality of articles to be operated on and arranged to move said articles successively into operative relation to said operating members, a pivoted actuating arm having a part to engage and actuate said conveyor, and having a hub provided with a shoulder, an operating device having a part to engage the shoulder on said hub and impart operative movement to said actuating arm, and means for connect-

ing said actuating device with said movable supporting member.

3. In a machine of the character described, an operating member mounted for rotation about a normally fixed axis, means for actuating said operating member, a movable supporting member, a second operating member rotatably mounted on said supporting member and movable therewith toward and from the first mentioned operating member, a conveyor having means for supporting a plurality of articles to be operated on and arranged to move said articles successively into operative relation to said operating member, a pivoted actuating arm having a part to engage and actuate said conveyor, and having a hub provided with a shoulder, and an operating device connected with said movable support to move the same toward and from the first mentioned operating member and having a part arranged to engage the shoulder on said hub and impart operative movement to said actuating arm when said supporting member is moved from said operating member.

4. In a machine of the character described, an operating member mounted for rotation about a normally fixed axis, means for actuating said operating member, a movable supporting member, a second operating member, rotatably mounted on said supporting member and movable therewith toward and from the first mentioned operating member, a conveyor having means for supporting a plurality of articles to be operated on and arranged to move said articles successively into operative relation to said operating member, a pivoted actuating arm having a part to engage and actuate said conveyor, and having a hub provided with a shoulder, an operating device connected with said movable support to move the same toward and from the first mentioned operating member and having a part arranged to engage the shoulder on said hub and impart operative movement to said actuating arm when said supporting member is moved from said operating member, and other means to return said actuating arm to its initial position.

5. In a machine of the character described, an operating member mounted for rotation about a normally fixed axis, means for actuating said operating member, a movable supporting member, a second operating member rotatably mounted on said supporting member and movable therewith toward and from the first mentioned operating member, a conveyor having means for supporting a plurality of gears and arranged to move said gears successively into operative relation to said operating members, a pivoted actuating arm having a part to engage and actuate said conveyor and having a hub provided with a shoulder, an operating device having a part to engage the shoulder on said hub and impart operative movement to said actuating arm, and means for connect-

toward and from the first mentioned operating member and having means for imparting operative movement to said actuating arm when said supporting member is moved from 5 said operating member, and a fluid operated device acting on said actuating arm to restore the same to its initial position.

6. In a machine of the character described, an operating member mounted for rotation 10 about a normally fixed axis, means for actuating said operating member, a movable supporting member, a second operating member rotatably mounted on said supporting member and movable therewith toward and from 15 the first mentioned operating member, a conveyor having means for supporting a plurality of articles to be operated on and arranged to move said articles successively into operative relation to said operating members, 20 a pivoted actuating arm having a part to engage and actuate said conveyor and having a hub provided with a shoulder, a fluid operated device connected with said movable support to move the same toward and from 25 the first mentioned operating member and having means for imparting operative movement to said actuating arm when said supporting member is moved from said operating member, a fluid operated device acting on 30 said actuating arm to restore the same to its initial position, the last mentioned fluid operated device being subjected to a constant pressure less than the operating pressure of 35 the first mentioned operating device, and means for controlling the operation of said first mentioned fluid operated device.

7. In a machine of the character described, an operating member mounted for rotation 40 about a normally fixed axis, a supporting member mounted for reciprocatory movement toward and from said operating member, other operating members carried by and movable with said supporting member, a fluid operated device for actuating said supporting member, a foot operated valve to control the operation of said fluid operated device, a conveyor having means to support a plurality of articles to be operated on and arranged to move said articles successively into operative 45 relation to said operating members, means controlled by said fluid operated device to advance said conveyor step by step, driving mechanism to rotate the first mentioned operating member, manually operated 50 means to initiate the operation of said driving mechanism, and means controlled by the operation of said driving mechanism to reverse the direction of rotation of said first mentioned operating member and to subsequently interrupt the rotation thereof.

8. In a machine of the character described, an operating member mounted for rotation 55 about a normally fixed axis, a second operating member, fluid operated means for moving said second operating member bodily

toward and from the first mentioned operating member, a foot operated valve to control the operation of said fluid operated means, means for rotatably supporting a gear in operative relation to said operating members, driving mechanism operatively connected with the first mentioned operating member, manually operated means for initiating the operation of said driving mechanism, means controlled by the operation of said driving mechanism to automatically reverse the direction of rotation of said operating member and to subsequently interrupt the operation of said operating member. 70

9. In a gear polishing machine, a plurality of rotatable polishing members mounted substantially in a common plane, means for rotating one of said polishing members, means for moving one of said polishing members transversely to its axis toward and from another of said polishing members, a conveyor having means for supporting a plurality of gears in spaced relation and arranged to move said gears between said polishing members, and means for intermittently operating said conveyor in timed relation to the movements of said transversely movable polishing member to move said gears successively into operative relation to said polishing members. 80

10. In a gear polishing machine, a plurality of rotatable polishing members mounted substantially in a common plane, means for rotating one of said polishing members, means for moving one of said polishing members transversely to its axis toward and from another of said polishing members, a conveyor having means to rotatably support a plurality of gears in spaced relation and arranged to move said gears between said polishing members, and means to intermittently actuate said conveyor in timed relation to the transverse movements of said polishing member to cause the same to move said gears individually into operative relation to said polishing members, to support the same during the polishing operation and to then withdraw the same from said polishing members. 90

11. In a machine of the character described, a plurality of operating members mounted for rotation in fixed planes, arranged to receive between them the article on which they are to operate and adapted to operate on said article when rotated in either direction, means to support an article in a position to be operated on by said member, driving mechanism connected with one of said operating members to rotate the same in operative engagement with said article, and a device controlled by said driving mechanism to reverse the rotation of said driven operating member and cause the same to operate on said article in the opposite direction. 110

12. In a machine of the character described, 120

a plurality of operating members mounted for rotation in fixed planes, arranged to receive between them the article on which they are to operate and adapted to operate on said 5 article when rotated in either direction, means to support an article in a position to be operated on by said member, driving mechanism connected with one of said operating members to rotate the same in operative engagement with said article, and a device controlled by said driving mechanism to reverse the rotation of said driven operating member and cause the same to operate on said article in the opposite direction, and to then 10 interrupt the rotation of said driven member after a predetermined period of operation in said opposite direction.

13. In a machine of the character described, a plurality of toothed polishing members mounted for rotation in a fixed plane, arranged to receive between them a toothed article to be polished and adapted to have polishing engagement with said article when rotated in either direction, means to rotatably 20 support a toothed article in mesh with the teeth of said polishing members, driving mechanism connected with one of said polishing members to rotate the same in polishing engagement with said article and thereby cause said article to rotate the other polishing member, and means controlled by said driving mechanism to automatically reverse the operation thereof and cause said polishing members to rotate in the opposite direction while in polishing engagement with said article.

14. In a machine of the character described, a plurality of toothed polishing members mounted for rotation in a fixed plane, arranged to receive between them a toothed article to be polished and adapted to have polishing engagement with said article when rotated in either direction, means to rotatably support a toothed article in mesh with the teeth of said polishing members, driving mechanism connected with one of said polishing members to rotate the same in polishing engagement with said article and thereby cause said article to rotate the other polishing member, and means controlled by said driving mechanism to cause said polishing members to make a predetermined number of rotations in one direction, to then make a predetermined number of rotations in the other direction and to then interrupt the rotation of said polishing members.

15. In a machine of the character described, a plurality of reversible polishing members mounted for rotation in a fixed plane, means to rotatably support an article in a position to be operated on by said members simultaneously, a reversible motor, means driven by said motor to rotate one of said polishing members in operative engagement with said article, switch actuating mechanism to con-

trol the direction of operation of said motor, and means for operatively connecting said switch actuating mechanism with said motor independently of the means for rotating said 70 polishing member.

16. In a machine of the character described, a plurality of reversible polishing members mounted for rotation in a fixed plane, means to rotatably support an article in a position to be operated on by said members simultaneously, a reversible motor, means driven by said motor to rotate one of said operating members, a switch actuating member, and a controlling device connected with said motor independently of said rotating means and actuated by the movement of said motor in one direction to move said switch actuating member to a position to reverse the direction of movement of said motor and actuated by the movement of said motor in the other direction to move said switch actuating member to a position to interrupt the operation of said motor.

17. In a machine of the character described, a plurality of reversible polishing members mounted for rotation in a fixed plane, means to rotatably support an article in a position to be operated on by said members simultaneously, a reversible motor, means driven by said motor to rotate one of said operating members, a switch actuating member, and a controlling device connected with said motor independently of said rotating means and actuated by the movement of said motor in one direction to move said switch actuating member to a position to reverse the direction of movement of said motor and actuated by the movement of said motor in the other direction to move said switch actuating member to a position to interrupt the operation of said motor, and manually controlled means to move said switch actuating mechanism to starting position.

18. In a gear polishing machine, a plurality of rotatable polishing members mounted substantially in a common plane, means for rotating one of said polishing members, means for moving one of said polishing members transversely to its axis toward and from another of said polishing members, a feeding device to move a gear into operative relation to said polishing members and to rotatably support the same during the polishing operation, and means controlled by the last mentioned means to advance said feeding device when said transversely movable polishing member is moved from said other polishing member.

19. In a machine of the character described, an operating member mounted for rotation about a normally fixed axis, means for actuating said operating member, and a supporting member movable transversely to the axis of said operating member, a second operating member rotatably mounted on said 120

supporting member and movable therewith toward and from the first mentioned operating member, an endless conveyor having a plurality of studs spaced apart lengthwise 5 thereof and each provided with means for supporting an article to be operated on, said conveyor being arranged to move said articles successively into and out of operative relation to said operating members, a device 10 adapted to engage a stud on said conveyor and actuate said conveyor, and means controlled by said supporting member for operating said device in timed relation to the movement of said supporting member.

15 20. In a machine of the character described, an operating member mounted for rotation about a normally fixed axis, means for actuating said operating member, a movable supporting member, a second operating mem-

ber rotatably mounted on said supporting member and movable therewith toward and from the first mentioned operating member, a conveyor having a plurality of studs spaced apart lengthwise thereof and each provided 70 with means for supporting an article to be operated on, said conveyor being arranged to move said articles successively into operative relation with said operating members, an actuating arm having a part to engage 75 a stud on said conveyor and actuate said conveyor, an operating device, and means for connecting said operating device with said movable support and with said actuating arm.

In testimony whereof, they affix their sig- 80 natures hereto.

THOMAS J. MULLEN.
WILLARD C. POWELL.
